UNITED STATES PATENT OFFICE.

ANTOINE LACROIX, JR., OF BROOKLYN, ASSIGNOR TO THE CO-OPERATIVE
BUILDING PLAN ASSOCIATION, OF NEW YORK, N. Y.

DESIGN FOR THE EXTERIOR OF A COUNTRY HOUSE.

SPECIFICATION forming part of Design No. 19,372, dated October 22, 1889.

Application filed September 28, 1889. Serial No. 325,455. Term of patent 3½ years.

To all whom it may concern:

Be it known that I, ANTOINE LACROIX, Jr., of the city of Brooklyn, in the county of Kings and State of New York, have invented and produced a new and original Design for the Exterior of a Country House, of which the following is a specification, reference being had to the accompanying drawings, forming a part thereof.

10 Figure 1 represents a perspective view of a country house of this design. Fig. 2 represents a horizontal section or plan of the first story. Fig. 3 represents a horizontal sectional view of the second story.

15 Similar letters of reference designate corresponding parts in all the figures.

A house of this design consists of two stories, with an attic third story included in a gable roof, the front being recessed at one side and gabled over the portion which is not recessed, the side adjacent to the recessed part of the front being also gabled and having bays in the second story, the back having bays of different form in the first and second stories, the recessed portion of the front, the whole length of the side above referred to, and a portion of the back as far as the bay being included on the second floor within a piazza, and there being a rectangular wing on the opposite side, which is also gabled, all as hereinafter more particularly described in detail with reference to the drawings.

10 A B C D designate the front of the house, of which the part D, including the first and

second stories, is recessed behind but parallel 35 with the parts A B C, which include the first, second, and attic stories, the said parts A B C being uniform through the first and second stories and the part C above them forming a gable in the attic story. The side E F G of 40 the house, which corresponds with the recessed portion D of the front, is of uniform width in the first and second stories and forms a gabled end in the attic story. The lower portion of this side E, belonging to the first 45 story, is flat, but the portion F above, belonging to the second story, has in it two octagonal bays a a. On the other side of the house is a wing H of rectangular form, the walls of which are plain. At the back of the house 50 there is on the first story a bay J, the plan of which consists of three sides of an octagon, and in the second story a bay K of rectangular form. On the first story there is a piazza I, which occupies the whole of the recess D 55 of the front and extends along the back as far as the bay J, this piazza having a shed or sloping roof L. The roof C' G' includes the front gable C and the side gable G, and also includes another gable H' above the wing H. 60

What I claim is—

The design for the exterior of a country house, substantially as herein shown and described.

ANTOINE LACROIX, JR.
